UNITED STATES PATENT OFFICE.

EMILE ERICSON, OF PELHAM, NEW YORK.

DESIGN FOR FABRIC.

46,122.

Specification for Design.

Patented July 21, 1914.

Application filed March 20, 1914. Serial No. 826,121. Term of patent 3½ years.

To all whom it may concern:

Be it known that I, EMILE ERICSON, a citizen of the United States, residing at Pelham, in the county of Westchester and State of New York, have invented a new, original, and ornamental Design for Fabrics, including high napped and pile fabrics, of which the following is a specification, reference being had to the accompanying drawing, forming part thereof.

Figure 1 shows a plan view of a portion of a fabric embodying my improved design, in which the heavy black portions show the plush form of the fabric and the shaded por-

tions the nap part of the fabric. The plush form is slightly raised beyond the nap form and the combination of the raised heavier black portion with the glossy black portion makes a very pleasing impression upon the eye. Fig. 2 is a section taken on line 2—2 of Fig. 1.

I claim:

The ornamental design for a fabric, as shown and described.

EMILE ERICSON.
